Attorney.

UNITED STATES PATENT OFFICE.

CARLOTTA FRANCES RODDEY, OF NEW YORK, N. Y., ASSIGNOR TO AUGUSTUS T. GURLITZ, OF SAME PLACE.

ABACUS FOR SLATES.

SPECIFICATION forming part of Letters Patent No. 339,933, dated April 13, 1886.

Application filed November 19, 1885. Serial No. 183,294. (No model.)

To all whom it may concern:

Be it known that I, CARLOTTA FRANCES RODDEY, residing in the city of New York, in the county and State of New York, have invented certain new and useful Improvements 5 in Educational Appliances; and I do hereby declare that the following is a full, clear, and exact description thereof, reference being had to the accompanying drawings, which form 10 part of this specification.

The object of this invention is to provide a device for instructing beginners, consisting of a number of beads or blocks of suitable shape arranged in a convenient holder, so as to be 15 separable and movable laterally, the holder being provided with characters or words corresponding to some quality of the movable portions when these are in certain positions, whereby their relative significance may be 20 easily and pleasantly conveyed to the mind of the learner.

Figure 1 represents a portion of a slate or blackboard containing my invention in one form. Fig. 2 represents a portion of a slate or 25 blackboard containing my invention in another form. Fig. 3 shows a ruler containing my invention. Fig. 4 is a section in the line xx of Fig. 1. Fig. 5 is a section in the line xx of Fig. 2. Fig. 6 is a section of my invention 30 when arranged on a slate-frame in a groove corresponding to the groove shown in Fig. 3. Fig. 7 is a cross-section on the line xx of Fig. 3.

Similar letters of reference indicate like parts in all the drawings.

35 A is a frame, in Figs. 1 and 2 forming a part of a slate or blackboard frame, and in Fig. 3 consisting of a ruler, and in this frame is provided a suitable slot, as B, in which are disposed a number of beads or other suitably- 40 shaped pieces, $b c d$, arranged so that they may be moved from one end of the groove to the other, leaving about a sixth or other suitable portion of the groove unoccupied to allow for moving about the blocks, &c., so that they 45 may be separated at various points, as desired. This frame or holder A may form or be in a portion of some other useful or educational appliance in the frames for a slate or blackboard, or in a ruler, as shown in the drawings, 50 or in any suitable or convenient box, case, or

other structure. So the blocks or beads may be retained in position by being strung on a rod or wire, a , as shown in Figs. 1 and 2; or they may be retained in place in any other suitable manner—for example, by being arranged in an inclined groove, B' , as shown in Fig. 3. On the margin of the frame, near the movable parts, their numbers are marked off in such position that when all of the blocks, &c., are pushed to the end where the figures 55 commence the proper block will be opposite its appropriate figure, as shown in Figs. 1, 2, and 3. This constitutes one form of my invention, and may be used alone, or in connection with the additions hereinafter described. This 60 is used to teach the child the correspondence between the number of things and the appropriate figure representing that number, as by moving one block to its position opposite the figure 1 it learns the numerical value of that 65 figure, and the same way with two or more. So the child may learn to add the numbers as two and two making four, which when pushed into place will show the figure of that value, so it may be taught to subtract, multiply, and 70 divide in primary sums of simple numbers in the same way. The figures on the margin 75 constitute examples for copying.

In some instances of my invention I further utilize the blocks for teaching by impressing 80 a letter upon each block, as shown in Fig. 2, in such order that by separating the blocks at some points various words may be formed, and by separating the blocks at other points different words may be formed by the use of 85 some of the same letters, the object being to intermingle the words and thereby interest the child in picking out the various words. In the example shown in the drawings, Fig. 2, the blocks have the letters arranged upon 90 them in this order—

NOWHERE ADMIT THE MULE LEARN NIGHT.

The letters numbered from 1 to 7 may be divided to form the words "no where" or "now here," from 6 to 9 will form the word 95 "read," from 8 to 12 "admit," 12 to 14 "the," 13 and 14 "he," 15 to 18 "mule," 17 to 21 "learn," 21 to 25 "night," and many other words may be arranged in the same way, whereby the child can learn to spell or pick out words, 100

and these letters may be impressed upon the block in the form of characters suitable for use as copies for writing. By thus arranging these lettered blocks in the frame of a slate or blackboard the child has not only the advantage of learning to divide the set of letters into various words, but also the further advantage of having ready to hand therewith a suitable surface upon which the different words may be at once written down, and thereby by children may use the same to exercise their ingenuity in picking out the words, and at the same time practice writing them down, without the necessity of any additional article to be carried along or mislead, as when a copy must be set separate from the thing upon which it is to be written. Besides, by having these character-blocks on a slate-frame advantage is taken of the imitative faculty of children, who, as a general rule, like to scribble, so that when they feel inclined to use the slate they find with it an attractive device to copy and arrange into various words.

In some instances of my invention I also color each of the blocks or beads of a different color. The primary, secondary, and tertiary colors may be grouped, if desired, and on the margin of the frame the names of the different colors are stamped, as shown in Fig. 3, in such position that when the blocks are shoved into place at the proper end of the groove the name of the color of each block will be opposite to that block. The child thereby learns to associate the name with the color, and the blocks may be pushed out of position and the child required to pick out a certain color, and then push the blocks into place to ascertain whether it has selected the proper color.

It will be seen from the foregoing description that the words or figures on the frame A indicate some characteristic of the blocks

which come opposite thereto when moved into position at one end of the slot, as the colors of the several blocks or the numerical value of the various blocks relative to each other, and this feature of the device will be found very useful in arousing the mental faculties of children.

Having thus described my invention, what I claim as new, and desire to secure by Letters Patent, is—

1. The educational device described, consisting of a holder, A, having movable blocks arranged therein, in combination with indicative characters on the frame opposite to the individual blocks, when the same are in position at one end of the limit of their movement, the blocks adapted to be moved away from such characters, substantially as described and shown.

2. In an educational device such as described, a set of colored blocks arranged to be moved from one side of the holder to the other, in combination with a suitable holder having the name of each color impressed thereon opposite the position which the block of that color will occupy when the blocks are on one side of the holder, substantially as described and shown.

3. The slate-frame A, having a slot, B, provided with movable blocks, in combination with the figures on the frame A, opposite to each block when the blocks are in position at one end of the slot, such slot being of sufficient length to permit the blocks being moved away from their respective figures, substantially as described and shown.

CARLOTTA FRANCES RODDEY.
